Alexander Chasin
his ATTORNEY

UNITED STATES PATENT OFFICE.

SAMUEL LOWY, OF NEW YORK, N. Y.

PARTITION PILASTER.

Application filed June 8, 1925. Serial No. 35,575.

My invention relates to pilasters for partitions in offices, stores and similar spaces, and more particularly to pilasters of an extensible type.

5 In an application filed by me on March 7th, 1925, Serial Number 13,711, I have shown a general type of such pilasters and partitions characterized by the property of being held in place by pressure, without the 10 use of nails and screws for attaching the pilasters and partitions to either floor or ceiling, whereby the deformation of the floors and ceilings characterizing present day methods is entirely avoided, no marks 15 being left when using my method in removing a partition or in making changes therein. Besides disclosing the general principle of holding partitions in place by pressure, I have shown in the aforesaid application 20 a specific type of pilaster as one of the illustrations of my general method. My present invention is concerned with another specific type of pilasters embodying the same general principle.

25 Inasmuch as these various types of extensible pilasters lend themselves with equal readiness to the construction of partitions, I am showing in the present case the structure of the pilaster alone, it being understood that various panels may be connected thereto either in the manner shown and claimed in the above mentioned application Serial Number 13,711, or in any other suitable manner.

35 Referring to the drawings, Fig. 1 is a vertical section through a pilaster embodying by present type; Fig. 2 is a cross section along the line 2—2 of Fig. 1; Fig. 3 is the upper part of the pilaster shown in Fig. 1, 40 abutting on the ceiling, with ceiling strip and cross rail in position; Fig. 4 is a cross section through said ceiling strip and cross rail, away from the pilaster; Fig. 5 is a detail of the base of the pilaster; and Figs. 6 45 and 7 are details of a modification of my device.

Referring to the above figures more in detail, my pilaster is composed of a main hollow post, 1, and an extension post 2, this extension post 2 being shown in Fig. 1 as elevated up to the ceiling 3. The main hollow post 1 rests in a shoe 4 having sharp-edged flanges or spikes 5 partly imbedded in the floor 6. Fitting into the main hol-

low post 1, at the base thereof, is a wooden block 7. On top of the block 7 lies a metal base plate 8, to which is affixed in any suitable manner, such as, for instance, the screws 9, a vertically extending post 10. This post 10 has a series of circumferential flanges 11. The post 10 is truncated by two parallel planes along its entire length, thus causing the flanges 11 to be interrupted. A tube 12 surrounds the post 10 and is formed at its lower end into two partial or interrupted, internal flanges 13 adapted to fit in between the flanges 11 of the post 10 for certain positions of the tube 12. The tube 12 is further provided with a collar 14, on which rests a supporting plate 15, the latter fitting slidingly into the main hollow post 1 and acting also in the capacity of a guide. On the supporting plate 15 rest facings 16 for the tube 12, these facings 16, together with the tube 12, constituting the extension post 2. The tube 12 has a plug 17 at its upper end. The plug 17 is perforated to permit the passage of the threaded stem 18 of the U-shaped member 19. A nut 20 on the stem 18, resting on a washer 21 interposed between said nut and the plug 17, is provided with holes 22 adapted to receive a pin or lever (not shown) for the purpose of turning the nut. A ceiling strip 23, trimmed to fit into the U-shaped member 19 so as to form a flush surface therewith, is braced underneath by a cross rail 24. A moulding 25 covers the face of the ceiling strip 23 and a part of the cross rail 24. On Fig. 4 is shown the manner of attaching glass or other panels to the pilaster extension, but as the manner of connecting panels to the pilaster does not form a part of the present invention, no further notations are indicated.

35 In Fig. 5 is shown in cross section the shoe 4 in which the main hollow post or the pilaster rests. The shoe is shown as external to the pilaster facings. This shoe may be concealed inside the facings of the pilaster by a slight and natural modification of design.

40 In Figs. 6 and 7 is shown a modification of the post 10. Instead of the interrupted flanges 11 of post 10, we have here the interrupted threads 11' on the post 10'. It is found that sometimes it is easier and cheaper to make interrupted flanges in this

manner, and it is to be understood that, in the claims, the word "flange", when describing this feature of my invention, may mean either the form 11 or 11', or any equivalents.

It should be noted that the main hollow post 1 is made up of the facings 26 and the fillers 27, the facings 26 having vertical grooves 28 within which the fillers 27 fit tightly. Other vertical grooves 29 in the facings 26 provide means for the sliding movement therein of the facings 16 of the tube 12.

The operation of my device needs but little explanation. When the pilaster is unextended, then the entire portion which, in Fig. 1, is shown above the main hollow post 1, remains below the moulding (not shown) covering the upper surface of the post 1 and is concealed thereunder. In this condition, the pilaster may be used for partitions which do not extend all the way to the ceiling. When it is desired to extend the pilaster to the ceiling, one would operate as follows.

The tube 12 is given a quarter turn, to release the internal flange 13 from engagement with the flange 11 on which it rested, whereupon the tube 12 is raised to the desired height, for instance, to the position wherein the U-shaped member 19 comes into close contact with the ceiling strip 23. The tube 12 is then given another quarter turn, which brings the flange 13 again into engagement with one of the flanges 11, thus securing the tube 12 in its elevated position. The adjustment is then completed as follows. The nut 20, which is preferably square, is turned by means of a lever inserted in one of the holes 22, the result of such turning being that the U-shaped member 19 moves upward. The U-shaped member 19 is prevented from turning with the nut 20 by the ceiling strip 23 which, it must be remembered, passes through at least two U-shaped members when a partition is being erected. The nut 20 is turned until the U-shaped member 19 exerts sufficient pressure on the ceiling strip and, through the ceiling strip, on the ceiling. The action of the mechanism at the upper end of the pilaster extension is comparable to that of a press. After the tube 12 has thus been jacked up, the facings 16 are raised up to the U-shaped member, the cross rail 24 is placed in position, and the moulding 25 is nailed unto the ceiling strip, cross rail and facings 16. Thus the entire structure is firmly locked in position.

I claim:

1. An extensible pilaster comprising a main hollow post, a second post extending longitudinally within said hollow post and fixed at the base thereof, a member surrounding said second post and movable relatively thereto, means for engaging said movable member with and for disengaging it from

said second post, a facing for said movable member adapted to form an extension of said main hollow post, and means for raising said facing when said movable member is raised.

2. An extensible pilaster comprising a main hollow post, a second post extending longitudinally within said hollow post and fixed at the base thereof, a multiplicity of circumferentially interrupted flanges on said second post, a pilaster extension composed of a tubular post and a facing therefor adapted to form an extension of said main hollow post, said tubular post surrounding said second post and having an interrupted internal flange adapted to engage one of said interrupted flanges on said second post when said tubular post is in a certain position and to become disengaged when said tubular post is given a predetermined turn from said position whereby said tubular post is released for longitudinal movement, and means for raising said facing of said pilaster extension when said tubular post is raised.

3. An extensible pilaster comprising a main hollow post provided with internal vertical guides, a body fitted thereinto at the base thereof, a second post fitted into said body and extending upward therefrom within said hollow post, a multiplicity of circumferentially interrupted flanges on said second post, a tubular post coaxial with and enclosing said second post, said tubular post being provided at its lower end with an interrupted internal flange adapted to engage one of said interrupted flanges of said second post for certain positions of said tubular post and to become disengaged for other positions thereof whereby said tubular post is released for longitudinal movement, a facing for said tubular post adapted to slide along said vertical guides in said main hollow post, and means for raising said facing when said tubular post is caused to rise.

4. An extensible pilaster comprising a main hollow post provided with internal grooves, a block fitted thereinto at the base thereof, a base plate on said block, a second post fitted into said plate and extending upward therefrom within said hollow post, a multiplicity of circumferentially interrupted flanges on said second post, a tubular post coaxial with and surrounding said second post, an interrupted internal flange at the lower end of said tubular post adapted to engage one of said interrupted flanges on said second post for certain positions of said tubular post and to become disengaged for other positions thereof whereby said tubular post is released for longitudinal movement, a collar on said tubular post, a supporting and guiding member on said collar slidingly fitted into said main hollow post, a facing for said tubular post resting on said supporting and guiding member and adapted to

slide along said vertical grooves of said main hollow post, a plug in the upper end of said tubular post, a hole in said plug, a U-shaped member having a threaded stem loosely fitting into said hole of said plug, a nut on said threaded stem above said plug, and means for turning said nut.

5. In a partition comprising a ceiling strip, a pilaster such as described in claim 10 4, said ceiling strip fitting into the U-shaped member forming part of the structure of said pilaster and preventing said U-shaped member from turning when it is forced upwards by the turning of the nut on the 15 threaded stem.

6. An extensible pilaster comprising a main hollow post and an extension member adapted to be raised longitudinally therefrom, means for holding said extension member in a fixed position relatively to said main hollow post and for releasing it from said position, and a press at the upper end of said pilaster adapted to be operated from above said extension member.

25 7. In a space between two fixed surfaces, an extensible post resting at one end on one of said surfaces and provided at the other end with a press separable therefrom, and means for extending said post to a position 30 where said press may be operated to cause said post to exert pressure on said surfaces.

8. In a space between two fixed surfaces, an extensible post resting at one end against one of said surfaces and provided at the other end with a press, means for extending said post to a position where said press may be operated to cause said post to exert pressure on said surfaces, and separate means for locking said post after such pressure is effected.

40 9. In an extensible pilaster, a post, a tube surrounding said post, means for holding said tube in a fixed position relatively thereto and for releasing it from said position for longitudinal movement, and a press adapted to be operated from above said tube.

10. In an extensible pilaster, a post, a multiplicity of interrupted flanges on said post, a tube surrounding said second post and provided at its lower end with an interrupted internal flange adapted to cooperate with said interrupted flanges on said second post to hold said tube in a fixed position relatively to said main hollow post and to release said tube for longitudinal movement, and a press at the upper end of said tube.

50 11. In a pilaster, a longitudinally adjustable extension therefor, and a press on said extension separable therefrom.

60 12. A pilaster comprising a stationary post, a member movable longitudinally with respect thereto, a press on said movable member, and facings movable with said

member and adapted to form an extension of said pilaster.

65 13. An extensible pilaster comprising a main hollow post, an extension member held in position within said hollow post but releasable for longitudinal movement, a pilaster extension between said main hollow post and said extension member, and means for raising said pilaster extension when said extension member is raised.

70 14. In an extensible pilaster between a floor and a ceiling, a main hollow post resting on said floor, an extension member adapted for longitudinal movement within said hollow post, means for holding and for releasing said extension member relatively to said hollow post, a supplementary extension at the upper end of said extension member provided with a press, and separate means for locking said extensible pilaster in position under pressure on said floor and ceiling.

75 15. In an extensible pilaster, a main hollow post, a second post extending upwards within said hollow post, an extension member on said second post adapted for longitudinal movement relatively thereto and comprising an extension of said main hollow post, means for holding said extension member at a fixed elevation, and means for releasing it for said longitudinal movement.

80 16. In an extensible pilaster, a pilaster extension adapted to be held at a fixed elevation, a pressure delivering element topping said pilaster extension and separable therefrom, and means for causing said pressure element to rise without turning.

85 17. In a pilaster, an extension member adapted for longitudinal movement relatively thereto, a cap topping said extension member, a hole in said cap, a pressure delivering element having a threaded stem loosely fitting into said hole, a nut on said threaded stem above said cap, means for turning said nut, and means for preventing said pressure delivering element from turning when said nut is turned.

90 18. In an extensible pilaster, an extension member adapted for longitudinal movement relatively thereto, and additional extension means on said extension member separable therefrom.

95 19. In an extensible pilaster, a stationary post, a jacket over said post adapted for longitudinal movement relatively thereto, a facing for said jacket separable therefrom and adapted to be moved therewith, stops along the length of said post, means on said jacket cooperating with said stops to hold said jacket in a raised position, and means for releasing said jacket from said position.
